(No Model.)

E. B. HAYES.
CUTTER HEAD FOR PLANING MACHINES.

No. 590,888.

Patented Sept. 28, 1897.

Mairi Fennick Hammer

UNITED STATES PATENT OFFICE.

ELI B. HAYES, OF OSHKOSH, WISCONSIN.

CUTTER-HEAD FOR PLANING-MACHINES.

SPECIFICATION forming part of Letters Patent No. 590,888, dated September 28, 1897.

Application filed July 17, 1896. Serial No. 599,541. (No model.)

To all whom it may concern:

Be it known that I, ELI B. HAYES, a citizen of the United States, residing at Oshkosh, in the county of Winnebago and State of Wisconsin, have invented certain new and useful Improvements in Cutter-Heads for Planing-Machines; and I do hereby declare the following to be a full, clear, and exact description of the invention, such as will enable others skilled in the art to which it appertains to make and use the same.

My invention relates to improvements in cutters or planers for planing-machines.

The invention consists of a cutter-head or planer comprising a core or shaft portion, fixed knives mounted upon the same, movable knives also mounted upon the same, and a longitudinal screw within said core for moving the movable knives longitudinally thereon.

The invention also consists of a cutter-head or planer comprising a core or shaft portion and knives mounted upon the same, so as to incline laterally and present an inclined cutting edge to the lumber being operated upon.

The invention also consists of certain other novel constructions, combinations, and arrangements of parts, all of which will be hereinafter more particularly set forth and claimed.

In the accompanying drawings, forming part of this specification, Figure 1 represents a top plan view of a cutter-head or planer embodying my invention. Fig. 2 represents a central vertical longitudinal section through the same. Fig. 3 represents a vertical transverse section through said cutter-head or planer, and Fig. 4 represents a vertical transverse section through a panel produced by the use of two of these cutter-heads or planers in a planing-machine such as shown and described in my pending application, Serial No. 599,540, filed July 17, 1896. Fig. 5 is a perspective diagrammatical view showing the manner in which the cut is made by the inclined knives. Fig. 6 is an end elevation of the core, showing the arrangement of the fixed knives, the journal being shown in section.

A in the drawings represents the core or shaft; B B, the stationary knives; C C, the movable knives; D, the operating-screw, and E E the slides supporting the movable knives.

The core or shaft A is suitably reduced at each end, so as to be capable of being journaled in the boxes of the planing-machine. 55 The middle portion of the core is rectangular in cross-section and is grooved at its longitudinal edges, as at a, said grooves being angular in formation and adapted to receive similarly-shaped flanges e, formed on the slides 60 E E. It will be observed from the above that the said slides can be moved freely along the core, but cannot move diametrically away from the same. The said core or shaft A is provided with a central longitudinal passage 65 a', in which is mounted the screw D. This screw is formed with a squared end d for receiving a wrench to revolve it and is held in position by a nut d', that screws into the end of the core and bears against a collar d² fast 70 on the said screw. The screw passes through a block d³, that is adapted to slide longitudinally in a slot d⁴ of the core or shaft. The slides E E, which are located upon opposite sides of the core, are connected to the opposite sides of this block d³, so as to move therewith when the screw is rotated.

Bevel-cornered cutting-knives C C are mounted upon each of the slides E E by bolts c c, that pass through slots c' c' cut therein. 80 By means of this latter construction the knives may be adjusted back and forth upon their respective slides so as to cut to a greater or less depth. These knives are set in laterally-extending grooves c² c², having inclined 85 bottom surfaces formed in the slides E E, and have inclined bottom surfaces, which cause one edge of the knife to sink lower than the other. The effect of this latter construction, when the cutter is in operation, is to cut a 90 shearing cut on an incline at each edge of the panel, and thus form a wedge-shaped edge on each side of the finished panel.

Knives C' C', similar in shape to knives C C, are preferably provided with thickened 95 portions upon their under sides to raise the cutting edges so that they will be upon the same plane with the cutting edges of the knives C' C', and are mounted upon the same sides of the core as said knives C C, but at the 100 opposite ends from the same. These knives are mounted directly upon the core in grooves similar to those occupied by the knives C C. These knives are provided with slots c',

through which pass pins or bolts c^5 , to adjustably attach them to the core.

The object in having the knives C C longitudinally adjustable upon the core or shaft 5 is to accommodate different widths of panels by increasing or decreasing the space between said knives. Longitudinal cutting-knives B B are secured upon the sides of the core not occupied by the knives C and C' by bolts b, 10 which pass through slots b', cut therein to permit the back and forward adjustment of the knives. These knives extend over the full length of the middle rectangular portion of the core, lapping over the edges of the 15 slides E E and projecting sufficiently beyond the edges of the same to form free cutting edges.

The knives C and C' of course extend to a greater degree over the edge of the core than 20 the knives B, as their office requires them to cut deeper into the lumber than said latter knives.

The great advantages of this cutter-head or planer are that it can be adjusted to the 25 desired width of panel by a single adjustment of the screw which operates the adjustable knives.

An inclined shearing cut is also secured by the disposition of the movable knives upon the 30 inclined bottoms of the grooves in the sliding blocks. One side of each of these knives being lower than the other, the higher side will therefore strike the material first, the rest of 35 the cutting edge following as the rotation advances.

All parts of the cutter-head or planer may also readily be taken apart for repairs.

Having thus described my invention, what 40 I claim as new, and desire to secure by Letters Patent, is—

1. A cutter-head or planer for a planing-machine comprising a shaft forming a core, fixed knives and movable knives secured upon 45 the same and a rotatable screw lying in the axis of said shaft and a diametrical block connecting the screw to said movable knives for moving them longitudinally thereon, substantially as described.

50 2. A cutter-head or planer for a planing-machine comprising a shaft forming a core provided with a central longitudinal slot, a block adapted to be adjusted in said slot lon-

gitudinally thereof, the said block extending entirely through said shaft laterally, knife-carrying plates secured to the opposite edges of said block and knives mounted upon said plates, and said shaft, substantially as described.

55 3. A cutter-head or planer for a planing-machine comprising a shaft forming a core, a rotatable screw lying in the axis of said shaft, adjustable knife-carrying plates connected to said screw so as to be adjusted longitudinally of said core and provided with 60 grooves having inclined bottom surfaces, said shaft also having grooves provided with inclined bottom surfaces and knives mounted in the grooves of said plates and shafts whereby they are inclined laterally so as to present 65 an inclined cutting edge to the lumber being operated upon, substantially as described.

70 4. A cutter-head or planer for a planing-machine comprising a shaft forming a core, a rotatable screw lying in the axis of the said 75 shaft, slides connected to said screw so as to be moved longitudinally of the core upon the rotation of said screw and knives mounted upon said slides, whereby knives on opposite sides of the shaft may be adjusted simultaneously and at one operation substantially as 80 described.

85 5. A cutter-head for a planing-machine comprising a shaft consisting of an integral core and journals, knives secured to said core, a screw passing through a journal and having its axis parallel with the axis of said shaft and means connecting said screw with some of the knives for adjusting them, substantially as described.

90 6. A cutter-head or planer for a planing-machine comprising a shaft forming a core and journals integral therewith, knives secured to said core, a screw passing through one of said journals and having its axis parallel with the axis of said shaft, means for adjusting said screw at the end of said journal and means connecting the screw with the knives for adjusting them, substantially as described.

100 In testimony whereof I hereunto affix my signature in presence of two witnesses.

ELI B. HAYES.
